Merritt Gally

UNITED STATES PATENT OFFICE.

MERRITT GALLY, OF NEW YORK, N. Y.

MECHANICAL MUSICAL INSTRUMENT.

SPECIFICATION forming part of Letters Patent No. 380,716, dated April 10, 1888.

Application filed August 2, 1887. Serial No. 245,990. (No model.)

To all whom it may concern:

Be it known that I, MERRITT GALLY, residing at New York city, in the county of New York and State of New York, have invented 5 certain new and useful Improvements in Musical Instruments, of which the following is a specification, reference being had therein to the accompanying drawing.

The accompanying drawing is a transverse 10 sectional view of an organ-action, showing the several parts of the invention in operating position.

The invention relates especially to musical 15 instruments which are operated mechanically, or mechanically and manually, but in part is also applicable to instruments which are operated only manually.

In the organ as shown the valves of the sounding devices are operated by pneumatic 20 motors which are in many respects similar to those shown in some of my former patents. I will here describe the peculiar features in this case of the construction and combination of the pneumatic motors and their 25 pneumatic vent-valves as forming a part of the present invention.

In my Patent No. 214,121, April 8, 1879, I show and describe a pneumatic motor for operating a sounding device for a musical instrument, which pneumatic motor is operated by 30 means of a primary pneumatic valve, which primary pneumatic and its valve are situated in a cavity forming a part of the wind-chest of the instrument, and the pneumatic motor 35 which the valve serves alternately to connect with the exhaust of the wind-chest and the external air is situated externally as to the wind-chest. In my Patent No. 346,152, July 27, 1886, I show and describe a primary pneumatic within the wind-chest, which operates 40 a pneumatic motor also placed within the wind-chest, an intervening valve acting in connection with the primary pneumatic, serving to open and close the port leading from the external atmosphere to the pneumatic motor. 45

In the present case I show the pneumatic motor P and the primary pneumatic k both placed within the wind-chest, the primary pneumatic serving to operate a valve which 50 alternately opens and closes the port of entry of the external atmosphere to the pneumatic

motor and the port leading from the pneumatic motor to the wind-chest.

The wind-chest A A' A² (shown in the drawing) is composed of three compartments freely 55 communicating with one another. This form of wind chest in compartments is not necessary to the construction or operation of the pneumatic action, and I make the wind-chest either with compartments or with a single 60 cavity to accommodate the arrangement of the other parts of the organ, as the case may require.

The grooved board B has inclosed grooves e, which lead from the pneumatic motors P, 65 and serve for alternately connecting the interior of the pneumatic motor with the external atmosphere and the wind-chest A A' A² through the ports of the valves or double valve a h. The valve a connects groove e with the 70 external atmosphere, and the valve h connects groove e with the wind-chest. The two valves a and h being connected together, one is open when the other is closed. The valve h, or a projection from it, rests on a thin flexible dia- 75 phragm, which, with a small cavity at the side of the diaphragm opposite the valve, forms a sensitive pneumatic for opening the valve. This valve-pneumatic connects with the tracker-range T through the leader-tube N, and with 80 the manual through a branch leader-tube, Z. The chamber of the valve-pneumatic connects through a very small opening, i, with the wind-chest A. The alternate opening and closing to the external atmosphere of the leader-tube 85 N by means of the perforated music-sheet y or the manual key F alternately connects groove e with the external atmosphere and the wind-chest A by means of the action of the pneumatic valve a h. Instead of two valve-but- 90 tons, a and h, one for each side of the grooved board B and connected together by means of the stem, as shown, a single button may be used, placed in a cavity in the grooved board, the interior ports being the seats for the valve, 95 the groove e leading into the cavity occupied by the valve.

It will be seen that with the construction as described groove e may be very much larger than if operated upon directly by the small 100 perforations of a music-sheet, and therefore the pneumatic P may be proportionately large

and powerful; or a greater number of pneumatics P can all be connected with the groove e and simultaneously operated thereby, as shown in the drawing.

5 The take-up roller M for the music-sheet y is shown connected by a belt to the wind-motor D , the valve for operating and controlling the wind-motor being at X .

In order that the feet may be rested from 10 pumping the bellows of the instrument while the music-sheet is being rewound, I use a hand-crank motor for rewinding the sheet, as shown in the drawing. On the shaft K of the hand-crank V is one of the members of a beveled gear, f . The shaft K has a lateral movement, which allows the beveled wheels ff' to be thrown in and out of connection. The beveled wheel f' drives the music-spool for rewinding the music. The gears are disconnected 15 when the sheet is being wound by the wind-motor on the take-up roller M .

In order to be able to operate the take-up roller at any time that the wind-motor may be deranged or out of repair, or to play passages out of regular time, to which the wind-motor is not perfectly adapted, I place a beveled wheel, n , on shaft K , which can be connected by a lateral movement of the shaft with beveled wheel n' and the take-up roller M , 20 driven by hand-crank V .

In order that the music-sheet may be wound or rewound while the air-tension remains in the instrument without producing any sound from the sounding device, I use a mechanism for 25 closing all of the stops of the instrument by

means of an auxiliary draw-knob, t , connected with the stop-rods $l m$, or any number of the draw-knobs, as r . On each of the stop-draws is a projection, c^2 . A pivoted swinging bar, a^2 , is operated by means of draw-knob t through 40 lever c .

It will be seen that any number of stop-knobs v , which may be drawn to open their stops, will all be forced back into closed position by drawing the single draw-knob t . This 45 secures the instantaneous closing of all the stops of the instrument when desired.

What I claim as my invention is—

1. In a mechanical musical instrument which is operated by means of a perforated or slotted music-sheet, the combination, with 50 the music-sheet, of a take-up roller and a wind-motor therefor and a hand-crank motor for rewinding the sheets.

2. The combination, with the music-sheet, the take-up roller, and the wind-motor therefor, of a hand-crank motor adapted to be used in lieu of the wind-motors when desirable, substantially as specified.

3. The combination, with the stop-rods, of 55 the swinging bar a^2 , the operating lever, and the supplemental draw-stop t , substantially as specified.

In testimony whereof I affix my signature in presence of two witnesses.

MERRITT GALLY.
